EVAPORATOR

Arthur R. Constantine, River Forest, Ill., assignor
to General Household Utilities Company, Chi-
cago, Ill., a corporation of Delaware

Application July 13, 1937, Serial No. 153,374

9 Claims. (Cl. 62—126)

My invention relates in general to evaporators or boilers and has more particular reference to the provision of an evaporator of simplified and inexpensive construction and designed especially for use in a refrigeration system.

An important object of the present invention is to provide an evaporator of simplified construction and particularly well adapted for use in refrigeration systems of the compressor-condenser-evaporator type, such as are commonly utilized in domestic or household refrigerators.

Another important object is to provide an evaporator or boiler having refrigerated shelves and adapted for fabrication from a minimum number of standard or stock parts.

Another important object is to provide an evaporator or boiler having refrigerated shelves fabricated by assembling a plurality of substantially identical plates providing internal ducts.

Another important object is to form an evaporator having one or more refrigerated shelves, each formed from a plurality of similarly shaped pipes.

Another important object is to provide an improved method of making evaporators for use in domestic or household refrigerators which consists in prefabricating a plurality of identical plates containing ducts and then assembling and securing the plates together to form side and bottom walls and interior partitions or shelves, all of said side, bottom and partition walls comprising plates of substantially identical construction.

Another important object is to provide a refrigerant evaporator of the character mentioned having simplified means for continuously ejecting a non-evaporable medium, such as oil, which may be carried into the evaporator with the refrigerant.

Another important object is to form the side and bottom walls of a refrigerant evaporator from a rectangular plate comprising a pair of sheet metal layers formed to provide internal refrigerant ducts between the layers by bending the plate to form spaced side walls and a bottom wall containing interconnected ducts, the evaporator including a separately formed header connected with the ducts of the side walls.

Another object is to provide an evaporator having spaced side walls containing refrigerant circulating ducts and having hollow shelf forming means for the circulation of refrigerant therein, said shelf means being mechanically supported on and between the side walls with the refrigerant space of said shelf means connected with the refrigerant ducts of the side walls; a

further object being to form the shelf means of pipe elements of substantially identical shape.

Another important object is to provide an evaporator having a header of simplified construction, the header comprising a cylindrical shell and being connected with the body of the evaporator by means of tubes extending between and secured to the walls of the cylindrical header-forming shell and the wall portions forming the remainder of the evaporator.

These and numerous other important objects, advantages, and inherent functions of the invention will become apparent as the same is more fully understood from the following description, which, taken in connection with the accompanying drawings, discloses a preferred embodiment of the invention.

Referring to the drawings:

Figure 1 is a perspective view of an evaporator embodying my present invention;

Figure 2 is a plan view of one side of a prefabricated plate containing internal ducts used in the construction of the evaporators shown in Figure 1;

Figure 3 is a plan view of the back of the plate shown in Figure 2 illustrating the manner of forming the plate to produce evaporator side wall elements;

Figure 4 is a plan view of the back of the plate shown in Figure 2 illustrating the manner of forming the plate for use as an evaporator partition or bottom wall;

Figure 5 is a top plan view of the evaporator shown in Figure 1;

Figure 6 is a front view of the evaporator shown in Figure 1, parts of the structure being shown in section to reveal structural details;

Figures 7, 8 and 10 are sectional views respectively taken substantially along the line 7—7 in Figure 1, the line 8—8 in Figure 5, and the line 10—10 in Figure 6;

Figure 9 is a sectional view similar to Figure 8 in order to illustrate a modified arrangement;

Figure 11 is a perspective view of a modified evaporator embodying my present invention;

Figure 12 is a sectional view taken substantially along the line 12—12 in Figure 11;

Figure 13 is a plan view of one side of a plate used in the evaporator assembly shown in Figure 11; and

Figure 14 is a perspective view of a shelf element which may be used in evaporators embodying my present invention.

To illustrate the invention, I have shown evaporators or boilers comprising preferably

sheet metal means arranged to form the side walls 13 and 15 and the bottom wall 17 of the evaporator. The side and bottom walls are hollow to provide enclosed interconnected spaces 5 for the circulation of an evaporable medium therein, and the evaporators also may include shelf means 19, preferably hollow and connected with the circulation spaces of the side walls 13 and 15 so that the evaporable medium may circulate in the shelf means also and refrigerate the same. In addition, the evaporators include header means 57 preferably separately formed and connected with the circulation spaces of the side walls 13 and 15 near the upper ends of the 10 walls by means of a plurality of conduits 63 which may be and preferably are all of identical shape.

As shown in Figures 1-7, the side walls 13 and 15 and the bottom wall 17 of the evaporator as well as the shelf or partition means 19 may comprise substantially identical elements providing 20 internal ducts for the circulation of a refrigerating or evaporable medium.

It is an important feature of the present invention to reduce the cost of making evaporators by 25 forming these wall elements 13, 15, 17, and 19 of substantially identical construction, and to this end each wall element comprises a pair of preferably sheet metal plates 21 and 23, the plate 21 being preferably flat and having diagonally cut 30 corners 25, and the plate 23 being formed with depressions 27 therein. The depressions 27 preferably comprise a plurality of spaced grooves or flutes 29 extending across the plate 23 and interconnected at the opposite ends of the grooves 29 35 by means of transverse grooves or flutes 31. The grooves 29 also are preferably interconnected by a transverse groove 33 extending intermediate the end connecting grooves 31 so that the arrangement of grooves 29 forms a grid-like pattern in the plates 23.

The plates 21 and 23 are assembled in facing relationship with the plate 21 closing the grooves 27 of the formed plate 23 so that said grooves form a network of internal ducts between the 40 plates 21 and 23, which are secured together by folding the lateral edges 35 of the plate 21 around the marginal edges of the plate 23 and by welding, soldering, brazing, or otherwise sealing the plates together at their edges and also, if desired, intermediate the grooved portions 29. Thus arranged, the connected plates 21 and 23 45 form standard or stock units which may be utilized in fabricating the condenser 11. The units, however, require certain additional drilling and forming operations to condition the same for assembly as the side, bottom, and partition walls in the evaporator. To prepare a stock unit for use as the side walls 13 and 15, I drill openings 37 in the plate 21 opposite one of the grooves 31. Additional openings 39 are also formed in the plate 21 in position opposite the opposed ends of the other groove 31, similar openings 41 being formed in the plate 21 opposite the opposed ends of the intermediate groove 33. In addition, the 55 stock elements forming the side wall 15 may have one of the grooves 31 flattened as at 43 in order to isolate from said groove 31 one of the grooves 29 for a purpose hereinafter more fully described. The groove 29 isolated in such fashion is, for 60 clarity, identified by the reference numeral 45.

In order to prepare the stock elements for use as a bottom or a partition wall in the evaporator, the plate 23 is perforated as at 47 in the ribs or 65 grooves 31 preferably opposite the ends of the 70 end-most grooves 29. The element forming at

least one of the walls 17 and 19 is also perforated as at 49, said perforation 49 preferably being made in the element forming the bottom wall 17 and being arranged in the plate 23 of said element in a groove 29 at one end of the element 5 opposite the ends of the connecting groove 33.

The elements 13, 15, 17, and 19 are assembled and secured in position with the plates 21 of the elements 13 and 15 in facing relationship, the elements 17 and 19 being arranged between the 10 facing surfaces of the elements 13 and 15 with the opposite edges of the elements 17 and 19 in position engaging the facing surfaces of said wall elements. The elements 17 and 19 also are preferably arranged with the plates 21 thereof facing 15 upwardly in order to provide relatively smooth shelf surfaces in the evaporator. The plates 17 and 19 may be secured to the elements 13 and 15 in any preferred manner as by welding, soldering, brazing, or otherwise securing the edges 20 upon the facing surfaces of the elements 13 and 15 and when so arranged the shelf elements form bracing means for holding and maintaining the side walls rigidly in spaced-apart, evaporator-forming relationship. The several duct systems 25 27 provided in all of the side walls are or may be interconnected by assembling tubular elements 51 in position between the openings 47 of the elements 17 and 19 and the openings 39 and 41 of the side wall elements 13 and 15, said openings 39 and 41 being disposed in registration with the openings 47 when the parts are assembled.

The tubes 51 are preferably mounted and secured in the elements 17 and 19 prior to the assembly of said elements between the said wall elements 13 and 15, the tubes 51 being inserted in the openings 47 and sealed thereto in any suitable fashion, as by welding, soldering, brazing, or similar fastening expedients. The tubes 51 so mounted have ends projecting outwardly of the opposed edges of the elements 17 and 19 in position to fit in the openings 39 and 41 of the wall elements 13 and 15 in order to facilitate the assembly operations which merely consist in mounting the elements 17 and 19 in position such that the ends of the tubes 51 extend in the openings 39 and 41. Thereupon the tubes 51 may be sealed in the openings 39 and 41 as by welding, soldering, brazing, or otherwise; and it is not necessary to provide additional fastenings although I prefer to join the edges of the plates 17 and 19 throughout the entire extent thereof with the adjoining surfaces of the elements 13 and 15 whereby to additionally strengthen the assembled structure.

The shelf means 19 may of course be made 55 in various ways, and while I prefer to make it as a plate of the type shown in Figure 4, especially if the side and bottom walls are made of similar plates, the shelf may however be conveniently and inexpensively made as shown in Figures 11, 12 and 14, wherein the shelf 19 comprises a pair of pipes 52 of preferably identical configuration.

These pipes preferably each comprise a long and a relatively shorter end portion in axial alignment and an intermediate loop portion extending laterally of and interconnecting said end portions.

The pipes 52 may be mounted by assembling the opposite ends of each pipe in the openings 60 41 in the opposing faces of the side wall elements 13 and 15, with the loop of each pipe 52 extending toward the long end portion of the other. All portions of both pipes are arranged in a common plane or zone and the pipe ends 70 75

are sealed as by silver soldering them in the openings 41. The several looped portions of the pipes may be secured together or otherwise braced to strengthen and rigidify the same. This 5 may be accomplished in the illustrated embodiment by applying a shelf element 54, shown in Figure 14, upon the tubes 52. The element 54 has a flat portion adapted to overlie the tubes and to which the tubes may be spot welded or otherwise secured. One edge of the element 54 10 may be curled as at 56 to fit upon the alined end portions of one of the tubes 52, and the opposite edge may be formed with a dependent flange 58 adapted to form a back stop for the shelf 15 space immediately below the pipes 52. The element 54 also may be embossed in any suitable or convenient manner to strengthen the same.

In Figures 11, 12 and 13 also I have shown how the side walls 13 and 15 and the bottom wall 17 may conveniently be fabricated as a unit by preforming a preferably rectangular plate 62 comprising a pair of preferably sheet metal layers 64 and 66. The layer 64 is or may be flat and formed with openings corresponding with the openings 37 and 41 in the separate elements forming the side walls 13 and 15 in the embodiment shown in Figure 1. The other element 66 of the plate 62 is preferably embossed to form flutes corresponding with the flutes 29, 31 and 33 in the several separate side and bottom wall elements of the embodiment illustrated in Figure 1. The plates 64 and 66 are then secured together as by folding the marginal edges 35 of the element 64 about the edges of the element 66 and/or by welding the plates together around their edges and, if desired, between the flutes 29. The plate 62 thus formed in flat condition may then be bent to form the spaced side walls 13 and 15 and the bottom wall 17, and the shelf 19, either of the sort shown in Figure 1 or the type illustrated in Figures 11, 12 and 14, may be applied as heretofore described.

The upper edges of the side wall elements 13 and 15 may be secured together in spaced apart relationship and braced by cross members 53, preferably comprising straps of sheet metal having lugs 55 by means of which the opposed ends of the strap members 53 may be welded or otherwise suitably secured to the upper edges of the wall elements 13 and 15. These strap members 53 may serve as handles for the convenient transportation of the evaporator and may also provide means for hanging the same in mounted position as in a refrigerator cabinet.

The evaporator, in addition to the wall portions 13, 15, 17, and 19, comprises a header 57 formed as a cylindrical container, one end 59 of which is preferably formed integral with the side walls of the container, the opposite end of the container being closed by means of a separately formed cover 61 suitably sealed thereon.

The header 57 is preferably mounted in the evaporator assembly on and between the side wall elements 13, and 15, with the longitudinal axis of the header 57 preferably extending at right angles with respect to the planes of said side wall elements, the header being preferably arranged substantially midway between the opposed ends of the evaporator. The header is attached to the side walls and connected with the duct systems 27 of the side walls by means of tubular connectors 63, there preferably being two connectors 63 at each end of the header for connecting the same with the adjacent side wall element of the evaporator. These connectors

are of simple construction, comprising lengths of pipe curved intermediate the ends thereof so that the end portions of the pipe extend at right angles. One end of each of the connectors 63 is fitted into and sealed in any preferred manner in an opening 65 in the lateral wall of the cylindrical header element 57 near an end thereof. The opposite ends of each connector when so mounted in the header element 57 extend in position to register with an opening 37 of the side wall element on which the header is mounted so that the header 57 may be fabricated with the connectors 63 attached and then assembled in position between the side wall elements 13 and 15 whereupon the connectors 63 may be sealed in place in position communicating with the openings 37.

The evaporator of my present invention is particularly adapted for use in refrigeration systems of the compressor-condenser-evaporator type which are commonly incorporated in domestic or household refrigerators. In such a refrigerating system, a suitable refrigerating medium is enclosed in a circulating system including a compressor in which the medium in gaseous form is compressed, a condenser in which the compressed medium is liquefied, and an evaporator to which the liquefied medium is delivered for evaporation and heat absorption, the refrigerant after evaporation in the evaporator being returned to the compressor for a repetition of the refrigerating cycle.

The evaporator of my present invention includes an inlet connection 65 for introducing the refrigerant into the evaporating space which, of course, comprises the interconnected duct systems 27 of the several wall elements as well as the space within the header which is connected by means of the pipes 63 with the said interconnected duct systems. The inlet connection 65 comprises a tubular element or pipe, one end of which is provided with means 67 for connecting the same in the delivery conduit of a refrigerant circulating system, the other end of said pipe being assembled and sealed in the opening 49, as clearly shown in Figure 10. Thus, a suitable evaporable medium may be delivered within the refrigerating space at the lowermost point thereof since the opening 49 is preferably arranged in the bottom wall element 17, as shown in Figure 6. The refrigerant is delivered through the inlet 65 directly into the connecting duct 33 of the wall element 17 and may escape thence through the ducts 29 into the end ducts 31 of the wall element 17. The refrigerant may then pass through the pipes 51 interconnecting the wall element 17 with the lowermost cross-duct 31 of the said side wall elements 13 and 15, whence the refrigerant may pass upwardly through the ducts 29 of side walls and into the upper cross-ducts 31 of said side walls and thence through the connectors 63 into the header 57. Some of the evaporable medium, of course, in passing upwardly through the duct system of the side walls 13 and 15 may penetrate through the connectors 63 which join the partition wall element 19 with said side walls.

The refrigerant delivery system may be arranged to maintain the refrigerant in the evaporation space of the evaporator to a level in the header indicated by the dotted line 71 in Figure 6, and it will be seen that the evaporable medium thus fills all of the internal duct space of the interconnected duct systems 27, including the internal duct system of the partition 19 as well

as the duct system of the bottom wall 17. In accordance with my present invention, the evaporators provide an unusually uniform refrigerating effect in all of the wall portions 13, 15, 17, 5 and 19. Heat absorption in a refrigerating system embodying the evaporator of my present invention is practically uniform in all the wall surfaces of the evaporator. Upon starting the refrigerating system in operation with the evaporator 10 extending in a humid atmosphere, it will be observed that frost commences to form on all of the heat transfer surfaces of the evaporator substantially simultaneously, thus indicating that the refrigerating effect is substantially uniform.

15 The evaporator also includes an exhaust connection 73 comprising a pipe having an end 75 sealed in an opening 77 formed in the header 57, said end 75 opening within the header 57 at a level about the liquid level 71. The exhaust connection 73 may be arranged as shown in Figure 8 20 with the end 75 opening downwardly into the header above the liquid level therein, or, as shown in Figure 9, the exhaust connection 73 may be arranged with its end 75 opening upwardly within the header above the liquid level therein.

25 The exhaust connection 73 may, of course, be provided with suitable means 79 connected thereon outwardly of the header and forming a connection for attaching the exhaust pipe with the suction side of a refrigerant circulating system.

30 Where the evaporator is used in a refrigerating system of the compressor-condenser-evaporator type in which it is necessary to provide adequate lubrication for the moving parts of the compressor, the refrigerating medium delivered to the evaporator may have absorbed therein varying quantities of the medium utilized in lubricating the compressor. Such lubricating medium ordinarily does not evaporate at the temperatures 35 prevailing in refrigerant evaporators and consequently may become entrapped in the evaporator space, and if not removed may accumulate in such quantities as to seriously impair the operation of the evaporator. To this end, I have provided means for continuously abstracting any 40 non-evaporable substance which may find its way into the boiler along with the evaporable medium. As heretofore mentioned, one of the side walls of the evaporator may be formed as at 43 to provide an isolated groove 45 comprising one of the grooves 29, such isolated groove 45 extending upwardly in the side walls and having a closed upper end. The oil extractor comprises a length of capillary tubing 81 which may be coiled as at 83 to accommodate the excess length of the tube in small compass. One end of the tube 81 is sealed as at 85 in an opening formed 45 preferably in the upper side of the discharge pipe 73. The other end of the tube 81 is sealed in an opening 87 formed in the upper end of the 50 standing isolated duct 45.

55 When the evaporator is in operation liquid will be delivered in the isolated duct 45 normally to an elevation above the opening 87 so that a portion of the liquid will enter the capillary tube 81 and be drawn thence to the discharge pipe 73. The capillarity of the tube 81, however, limits the 60 amount of liquid that can thus be withdrawn. The pipe 81, however, provides for continuously 65 extracting from the evaporator liquid containing any non-evaporable substance which may reach the evaporator with the evaporable medium; consequently, such non-evaporable substance is drawn out of the evaporator and discharged 70 through the outlet pipe 73 in order to prevent the

75 evaporator from becoming filled with such non-evaporable substance. It will be noted that the capillary extractor tube 81 is exposed in the atmosphere surrounding the evaporator which, of course, will usually be higher than that prevailing in the liquid in the evaporator space. Liquid drawn into the tube 81 from the evaporator space and containing a non-evaporable substance dissolved or otherwise incorporated with the evaporable medium would, of course, be exposed to the 10 temperature of the surrounding atmosphere during its passage through the tube. The evaporable constituent of the medium may evaporate in tube 81 leaving the non-evaporable substance in the form of successive slugs of liquid filling the tube, the successive slugs being separated by a quantity of the evaporable material in gaseous condition. These successive liquid and gaseous bodies, however, will be drawn through the tube and into the discharge pipe 73.

15 The device of my present invention is relatively inexpensive to make since it embodies standard wall units of substantially identical construction which may be readily formed to provide side, bottom, and partition wall elements which may be 20 easily assembled and secured together to form the finished evaporator. The header element also is of simple and inexpensive construction and is adapted for ready assembly in position between the side wall elements 13 and 15. The evaporator 25 also provides an unusually efficient heat transfer unit since not only the side walls and bottom wall, but also the partition wall provide for the evaporation of the medium. I find that the particular arrangement which I have illustrated and 30 described herein has an unusually uniform heat 35 transferring effect throughout all of the surfaces of the wall elements, thereby promoting maximum evaporator efficiency.

40 It is thought that the invention and its numerous attendant advantages will be understood from the foregoing description and it is obvious that numerous changes may be made in the form, construction, and arrangement of the several parts without departing from the spirit or scope 45 of the invention and without sacrificing its attendant advantages, the forms herein described being preferred embodiments for the purposes of demonstrating the invention.

45 What I claim is new and desire to secure by Letters Patent of the United States is:

1. An evaporator or boiler comprising spaced 50 side wall elements and an intermediate partition or shelf element, said elements having substantially identical structural arrangement and comprising each a pair of cooperating plates formed to provide therebetween a plurality of parallel 55 grooves interconnected by transverse grooves at and intermediate the opposed ends of the parallel grooves to provide between the plates of each element a system of interconnected ducts, connector means communicating with the duct systems of said side wall elements through openings in the facing plates thereof and communicating with the duct system of the shelf element where- 60 by to interconnect the duct systems of said elements, and means forming a header chamber in communication with the duct systems of said side wall elements.

65 2. An evaporator or boiler comprising spaced 70 side wall elements and an intermediate partition or shelf element, said elements having substantially identical structural arrangement and comprising each a pair of cooperating plates formed to provide therebetween a plurality of parallel 75

grooves interconnected by transverse grooves at and intermediate the opposed ends of the parallel grooves to provide between the plates of each element a system of interconnected ducts, connector means communicating with the duct systems of said side wall elements through openings in the facing plates thereof and communicating with the duct system of the shelf element whereby to interconnect the duct system of said elements, and means forming a header chamber in communication with the duct systems of said side wall elements, the means forming the header chamber comprising an elongated tubular casting, the opposite ends of which are connected, respectively, with the upper portions of the duct systems of said side wall elements.

3. An evaporator or boiler comprising spaced side wall elements and an intermediate partition or shelf element, said elements having substantially identical structural arrangement and comprising each a pair of cooperating plates formed to provide therebetween a plurality of parallel grooves interconnected by transverse grooves at and intermediate the opposed ends of the parallel grooves to provide between the plates of each element a system of interconnected ducts, connector means communicating with the duct systems of said side wall elements through openings in the facing plates thereof and communicating with the duct system of the shelf element whereby to interconnect the duct systems of said elements, and means forming a header chamber in communication with the duct systems of said side wall elements by means of connector tubes opening laterally into the header, the said tubes being bent intermediate their ends for connection with the facing surfaces of said side wall elements.

4. An evaporator or boiler comprising spaced side wall elements and an intermediate partition or shelf element connected between the side wall elements, said elements having substantially identical structural arrangement and comprising each a pair of complementary sheet metal plates, at least one of which is formed with a plurality of parallel grooves therein and transverse grooves interconnecting said parallel grooves at and intermediate the ends thereof and another of which plates is secured to the grooved plate in position closing the grooves to form a system of interconnected ducts within the element, said shelf or partition element being assembled between the side wall elements with its opposed edges extending adjacent the opposing faces of said side wall elements opposite a transverse groove of each of said side wall elements, means interconnecting each of a pair of the transverse grooves of said shelf or partition element respectively with a transverse groove of each of said side wall elements, and means forming a header chamber interconnected with the duct systems of said side wall elements.

5. An evaporator or boiler comprising spaced side wall elements and a plurality of intermediate partition elements including a bottom wall element and a shelf element, the shelf element being connected between the side wall elements in vertical spacing with respect to the bottom wall element, said elements having substantially identical structural arrangement and comprising each a pair of cooperating plates formed to provide therebetween a plurality of parallel grooves interconnected by transverse grooves at and intermediate the opposed ends of the parallel grooves to provide between the plates of each ele-

ment a system of interconnected ducts, the duct systems of said partition elements being connected each with the duct systems of both of said side wall elements, said partition walls being assembled between the side wall elements each with its opposed edges in position substantially registering with corresponding transverse grooves in said side wall elements and tubular connectors sealed upon said partition and side wall elements and communicating one of the transverse grooves of the partition wall with a transverse groove of a side wall and communicating another transverse groove of the partition wall with a transverse groove of the other side wall.

6. An evaporator or boiler comprising spaced side wall elements of substantially identical construction, each comprising a pair of cooperating sheet-metal portions formed to provide therebetween a plurality of parallel, vertically extending ducts in said side wall elements interconnected by a transverse duct at the upper end of said parallel ducts to form an interconnected duct system in each of said side wall elements, means interconnecting said duct systems below the transverse ducts, means forming a header chamber connected to the transverse duct of each side wall element, at least one of said side wall elements being formed to isolate the upper end of at least one of said duct portions, means forming an outlet on said header, and means forming a capillary channel connecting the upper end of said isolated duct with said outlet.

7. An evaporator or boiler comprising spaced side wall elements of substantially identical construction, each comprising a pair of cooperating sheet-metal portions formed to provide therebetween a plurality of parallel, vertically extending ducts in said side wall elements interconnected by a transverse duct at the upper end of said parallel ducts to form an interconnected duct system in each of said side wall elements, means interconnecting said duct systems below the transverse ducts, means forming a header chamber connected to the transverse duct of each side wall element, at least one of said side wall elements being formed to isolate the upper end of at least one of said duct portions, means forming an outlet on said header, and means forming a capillary channel connecting the upper end of said isolated duct with said outlet and comprising a tube connected at its opposite ends in said isolated duct portion and in said outlet and having the intermediate portions of the tube arranged in coils.

8. An evaporator or boiler comprising spaced side wall elements of substantially identical construction, each comprising a pair of cooperating sheet-metal portions formed to provide therebetween a plurality of parallel, vertically extending ducts in said side wall elements interconnected by a transverse duct at the upper end of said parallel ducts to form an interconnected duct system in each of said side wall elements, means interconnecting said duct systems below the transverse ducts, means forming a header chamber connected to the transverse duct of each side wall element, at least one of said side wall elements being formed to isolate the upper end of at least one of said duct portions, means forming an outlet on said header, and means forming a capillary channel connecting the upper end of said isolated duct with said outlet, said capillary channel forming means comprising a tubular element connected at one end in said

isolated duct portion and connected at the other end in the upper side of said outlet.

9. An evaporator or boiler comprising spaced side wall elements and an intermediate partition or shelf element, said elements having substantially identical structural arrangement and comprising each a pair of cooperating plates, one of which is formed with a plurality of parallel grooves interconnected by transverse grooves at 10 and intermediate the opposed ends of the parallel grooves, the other plate being flat and secured to the grooved plate in position to overlie the grooves thereof to form a duct system between the plates, said side wall elements being ar-

ranged with the flat plates thereof in facing relationship and said shelf element being arranged between the side wall elements with the flat plate of the shelf element facing upwardly between the side wall elements, means interconnecting the duct systems of the shelf and side wall elements and header forming means interconnected with the duct system of each of said side wall elements, an outlet or suction connection on said header and an inlet connection on 10 one of said shelf forming elements and communicating with the duct system thereof. 5

ARTHUR R. CONSTANTINE.
